UNITED STATES PATENT OFFICE.

ONESIME H. LE COMPTE, OF ST. LOUIS, MISSOURI, ASSIGNOR TO LE COMPTE STAND-
ARD AUTOMATIC DRAWBAR AND CONNECTOR COMPANY, OF DENVER, COLORADO,
A COMMON LAW TRUST.

CAR COUPLER.

Application filed February 16, 1921. Serial No. 445,471.

To all whom it may concern:

Be it known that I, ONESIME H. LE COMPTE, a citizen of the United States, residing at St. Louis, State of Missouri, have 5 invented new and useful Improvements in Car Couplers, of which the following is a specification, reference being had to the accompanying drawings.

My invention relates to improvements in 10 combined automatic car and train line couplings.

My primary object is to provide means of 15 simple and inexpensive construction which will operate, with certainty under all ordinary conditions, to automatically couple cars and simultaneously with the coupling of the cars make connections in the train lines, such as steam pipes for heating, air pipes for signal and brake purposes and 20 conductors in electric light circuits.

A further object is to construct a coupler 25 of the combined car and train line type in a manner facilitating assemblage, having special regard for the reducing the repair or upkeep expenses.

A still further object is to construct the 30 car coupling elements and the train line coupling elements as distinct structures and to provide means for their ready relation which latter means includes devices for adjusting the train line coupling elements with 35 relation to the car coupling elements in order to "set" the former elements in positions to function properly.

A still further object is to construct a car 40 coupling comprising a relatively fixed jaw co-operating with a gravity operating pin both of which have related means to function without extraneous elements such as 45 springs.

A still further object is to provide a 50 simple means for connecting the two pins of connected car couplings for synchronous uncoupling movement and to provide at least 55 one of the pair of couplings with a simple means for moving its pin to affect uncoupling.

With the foregoing objects in view, my 60 improvements consist in the novel construction, arrangement and combination of parts as hereinafter fully, clearly and concisely set forth, definitely pointed out in my claims and illustrated by the accompanying drawings, in which:

Figure 1 is a plan view of a pair of cou-

plings, in coupling position, constructed in accordance with my invention.

Figure 2 is an elevation of the couplings, as shown in Figure 1.

Figure 3 is a longitudinal, vertical sec- 60 tional elevation taken on the line 3—3 of Figure 1.

Figure 4 is a sectional plan view taken on the line 4—4 of Figure 2.

Figure 5 is a front elevation of one of the 65 couplings.

Figure 6 is a transverse sectional view taken on the line 6—6 of Figure 1 looking in the direction of the arrow.

Figure 7 is a transverse sectional view 70 taken on the line 7—7 of Figure 1 looking in the direction of the arrow.

Figure 8 is an enlarged, front elevation of one of the coupling pins.

Figure 9 is a side elevation of the coupling 75 pin.

Figure 10 is a longitudinal sectional elevation of a single coupling head and drawbar showing the means for automatically holding the head aligned with the drawbar. 80

Figure 11 is a plan view showing a head 85 and drawbar as upon cars which are relatively non-aligned.

Referring by numerals, to the drawings, A and B designate the heads of the coupling, 90 which are identical structures and which are preferably of cast construction and whose design permits both to be formed in the same mold with a resultant economy in construction to which is added the feature that any coupler of this type may be employed 95 at either end of any car.

Inasmuch as the two heads are identical I 100 will describe in detail the one head only, as follows:

Projecting forwardly from the front of the head is a fixed jaw 1, occupying a position wholly to one side of the longitudinal median line, and which has formed on its inner face a vertical recess 2. On its outer, lateral face the jaw 1 is provided with a longitudinal tapering rib 4.

The jaw 1 with its recess 2 and rib 4 is 105 preferably formed as an integral part of the head and said head except for the base of said jaw is formed as a hollow shell, comprising a top wall 5, a bottom wall 6 and side walls 7 and 8.

The opening 9, formed by the space be- 110 tween the base of the jaws 1 and the walls

5, 6 and 8, is of substantially the same area and contour as the jaw 1 and is arranged to receive the jaw of a companion coupling, and, the wall 8 is provided with a way 10, 5 of longitudinal tapering formation for the reception of the rib 4 of the companion coupling, and by this expedient the two heads are brought to the same plane when brought together.

10 Projecting laterally from the base of the jaw toward the wall 8 is a stud 11 whose forward upper and lower corners are chamfered and formed in the inside face of the jaw is a longitudinal channel 12 for the ac-

15 commodation of the stud of the companion coupling, and by preference the forward lower corner of the channel is chamfered to coact with the chamfer of the stud 11 to guide the jaw in the head of its companion.

20 Formed through the top and bottom walls 5 and 6, respectively, immediately to the rear of the base of the jaw are the holes 13 and 14, the hole 14 being located wholly to one side of the median line of the head while 25 the hole 13 is of greater area and extends over, or spans, the median line, as best shown in Figure 3, and formed in the top wall in advance of the hole 13 is a notch 15.

Formed in the side wall 7 immediately 30 to the rear of the holes 13 and 14 is a slot 16, and formed in the top wall 5 and bottom wall 6 adjacent the rear, open end of the head are the relatively aligned holes 17 and 18.

35 On the inside faces of the side walls 7 and 8 transversely aligned with the holes 17 and 18 are the opposite vertical ways 20 and 19.

The holes 13 and 14 are arranged to receive the coupling pin 21, (Figures 8 and 9) whose body or stem is preferably of rectangular or non-circular section and said stem carries at its inside lateral face a lifting stud 22 whose forward lower corner is 40 chamfered for elevation by the lower, forward chamfer of the channel 12 of the jaw. For the same reason the pin is provided with a second elevating element, such as 23 arranged to be moved by impingement with 45 the upper forward corner 24 of the jaw.

At the top the pin is provided with a head 25, which determines its lower limit of movement and projecting forwardly from the head 25 there is a dowel 26 located to 55 one side of the median line while formed in the head 25 on the other side of the median line there is a dowel seat 27.

The pin is further provided with a manipulative element 21^a arranged for extension through the slot 16.

Formed on the bottom face of the lower wall 6 of the head there are the parallel guides 28-28, and a stop 29 having a set screw 30, suspended from which guides is 65 a manifold 31, formed en-bloc, in which is

formed a plurality of passageways, terminating at their rear ends in laterally projecting couplings 32 for connection with train lines and at their forward ends in forwardly projecting gasket couplings 33 for connection with similar gasket coupling on a companion manifold.

70 The drawbar 34 comprises a head 35 whose section permits it to be extended freely into the rear open end of the head 75 1 and through which there is formed a hole 36 for the reception of the pin 37 which extends through the holes 17 and 18 in the head 1.

75 As shown the head 35 is provided with an integral perforated strap 38 spaced from the lower side of the head 35 through which the pin extends and positioned between the head and strap is a floating key-plate 39 perforated to receive the pin 37 and provided 80 with wings 40 which loosely reside in the ways 19 and 20.

85 By this latter expedient the pin will be capable of connecting the head 1 with the drawbar even though it may be broken within its length.

90 Extending rearwardly from the head 35 of the drawbar is a bifurcated stem 41 provided with a contracted mouth 42 at its rear end which is arranged to receive the end 43 95 of the drawbar proper 44.

95 The end 43 is provided with shoulders 45 which fit over the reduced mouth of the stem 41 and serve to connect the drawbar elements in a manner to prevent relative 100 longitudinal movement yet be capable of slight vertical movement for imparting to the coupling as a whole limited vertical flexibility for purposes of relatively aligning two coupled couplings to thereby 105 prevent breakage of the pin connections when the coupled cars are longitudinally out of alignment.

110 As shown the forward ends of the fixed jaws 1 are inclined rearwardly and inwardly so that in the event the heads are swung on the pins 37 to not align with the trends of the cars such jaws will coact to swing the coupler head to relative alignment.

115 In Figure 10 I show the upper forward corner of the head 35 of the drawbar as provided with a cam-chamfer 35^a and the coupling head with a bevelled rib 35^b extended transversely thereof and depending from its upper wall 5.

120 By this expedient the coupling head by reason of the beveled rib and the chamfer of the drawbar is gravity actuated to tend toward alignment with the drawbar and thus facilitate the coupling of two cars and their train lines.

125 In the act of coupling two cars equipped with couplers constructed as just recited, the chamfers on the jaw 1 engage the cham-

fer studs 23 and 22 and thus lift the coupling pin 21 to permit the jaws to enter the heads to a point where the recesses 2 of the jaws will reside within the coupler heads and to the rear of the coupling pins so that the heads 25 of the pins will be dropped into the jaw recesses 13 and thereby form a double or two pin coupling.

Particular attention is drawn to the fact that there are two locking jaws and two coupling pins and that the pins are automatically operated, that is, lifted, by the jaws and fall by gravity to coupling positions, all without the intervention of springs or other extraneous devices.

The pins and jaws serve to hold the coupled heads against movement in any direction, but by reason of the pivotal connection, in, the pins 37 the heads have flexure relative to the drawbars.

An uncoupling is affected by an elevation of the coupling pins, which is accomplished by lifting the element, or handle, 21^a, which by reason of the dowel connection between the two pins raises both coupling pins at the same time thereby releasing both jaws.

An economical advantage arising from the construction of the couplings as described is that due to the making of the structure in a number of parts such as the head proper, the pins, and the two part drawbar the assemblage is facilitated and the replacement of broken or damaged pieces much reduced in cost over such couplings as are cast or formed in one piece.

What I claim as new is:

1. In a coupling construction, a draw bar, a shell like coupling head provided with an integral stationary knuckle and carried pivotally and vertically movable by said draw bar, a gravity actuated locking pin passing completely through the coupling head, and means for automatically elevating the locking pin by the knuckle of a companion coupler during coupling engagement.

2. In a coupling construction, a draw bar, a shell like coupling head provided with an integral stationary knuckle and carried pivotally and vertically movable by said draw bar, said knuckle having a vertically disposed recess formed in its inner face and a longitudinally disposed channel formed in its inner face to provide two bearing surfaces one of which is disposed above the inner end of the longitudinal channel and one below the inner end of the channel, and a vertically movable locking pin having elements for engaging the said two bearing surfaces of a companion coupler when two like couplers are in coupled engagement.

3. In a coupler construction, a pair of draw bars each carrying a head member provided with a pivotal connection with its draw bar affording also vertical movement

of the head members, an integral knuckle member carried by each of said head members having chamfered surfaces, a vertically movable locking pin having laterally extending knuckle engaging lugs each provided with a chamfer carried by each head member and adapted when in lowered position, for coupling engagement with the knuckle member of the companion head member and when in raised position to release said knuckle member of the companion head member.

4. In a coupling construction, a draw bar, a coupling provided with a rigid knuckle member and carried pivotally and vertically movable by said draw bar, and a vertically movable locking pin having laterally extending elements adapted for coupling engagement with a companion coupler and operative when in coupled relation to prevent uncoupling of the couplers.

5. In a coupler construction, a draw bar, a coupling head provided with a stationary knuckle member having two bearing surfaces and with a connection to said draw bar permitting pivotal and vertical movement of said head with reference to said draw bar, and a vertically movable gravity locking pin having laterally extending elements adapted for coupling engagement with a companion coupler and operative when in coupled relation to prevent uncoupling of the couplers.

6. In a coupler construction, a pair of draw bars each carrying a head member provided with a coupler element and a vertically movable gravity locking pin provided with laterally extending elements carried by each head member and adapted for automatic locking engagement with the stationary coupler element of the other head member and said gravity locking pin passing completely through each head.

7. In a coupler construction, a pair of draw bars each carrying a head member provided with a stationary integral element having a beveled face portion and a vertically movable gravity locking pin provided with laterally extending elements carried by each head member and adapted to be lifted by engagement with the coupler element of the other head member and thereafter dropped into locked relation therewith.

8. In a coupling construction, a pair of draw bars each carrying a hollow head member provided with a pivotal connection with its draw bar affording also vertical movement of the head members, a stationary knuckle member carried by each of said head members having a vertical recess and chamfered surfaces, a vertically movable locking pin having laterally extending knuckle engaging elements each provided with a chamfered surface carried by each head member and passing completely

through each head member and adapted when in lowered position for coupling engagement with the knuckle members of the companion head member and when in raised position to release the knuckle member of the companion head member.

9. In a coupling construction, a draw bar, a shell like coupling head provided with a stationary knuckle having a vertical and a horizontal recess and carried pivotally and vertically movable by said draw bar, a vertically movable locking pin having laterally

extending chamfered lugs carried by the coupling head adapted for coupling engagement with the knuckle of a companion coupling head, the lowermost of said chamfered lugs adapted to pass through the horizontal recess of a companion coupling head and elevated by the lower surface thereof to permit automatic coupling of the 20 coupler heads.

In testimony whereof I hereunto affix my signature.

ONESIME H. LE COMPTE.
